UNITED STATES PATENT OFFICE.

EDWARD C. STEARNS, OF SYRACUSE, NEW YORK.

DOOR-HANGER.

SPECIFICATION forming part of Letters Patent No. 321,151, dated June 30, 1885.

Application filed September 23, 1884. (No model)

To all whom it may concern:

Be it known that I, EDWARD C. STEARNS, of the city of Syracuse, in the county of Onondaga and State of New York, have invented 5 a new and useful Improvement in Door-Hangers, of which the following is a specification.

This invention relates to an improvement in that class of door-hangers which are employed for supporting sliding doors from the top, and 10 which consist of rollers or wheels which run on horizontal rails above the door and an adjustable bearing supported by the rollers and secured to the upper edge of the door.

The object of my invention is to so construct 15 the hanger that it can be easily adjusted, whereby the door will hang perfectly true, and that it is simple in construction and durable.

My invention consists to this end in the particular construction of the hanger, as will be 20 hereinafter fully described, and pointed out in the claims.

In the accompanying drawings, Figure 1 represents a side elevation of a door-hanger provided with my improvements and applied to 25 the upper edge of a door. Fig. 2 is an end elevation thereof. Fig. 3 is a fragmentary longitudinal section on an enlarged scale; and Fig. 4, a cross-section in line x x , Fig. 3. Fig. 5 is a perspective view of the cylindrical nut.

Like letters of reference indicate corresponding 30 parts in the several figures.

A represents the upper portion of a sliding door, and B B the horizontal rails, arranged above the door in the usual manner.

35 C C represent the rollers or wheels of the hanger, which are secured to a shaft, c, at the proper distance apart to run upon the rails B B. The rollers C C are preferably provided with flanges c', whereby they are held in position on the rails.

D represents the rider-bar, which rests on the shaft c between the rollers C C. The rider-bar D consists of two horizontal bars, d d', and end portions, d² d³, which connect the horizontal bars at their ends, the horizontal bars d d' and end portions being cast in one piece. The lower edge of the upper bar, d, is made straight and rests on the shaft c of the rollers.

E represents the base-plate of the hanger, 50 which is fastened to the upper edge of the door A in any suitable manner. The plate E is pref-

erably provided along its lower edge with inclined ledges e e, which fit between ears or lugs k k, having inclined inner sides and formed on a horizontal plate, K, which is secured to 55 the upper edge of the door by screws l. The plate E is attached to the horizontal plate K by sliding its lower edges between the lugs k k, and when adjusted to its proper place it is firmly secured to the plate K by a horizontal 60 screw-bolt, m, which is inserted in a threaded opening formed at the outer end of the plate K.

f f' represent connecting bars or links, pivoted at their lower ends to the plate E and at their upper ends to the lower bar, d', of the 65 rider-bar, whereby the latter is secured to the base-plate E. The links f f' are secured to opposite sides of the rider-bar and base-plate, and are preferably made in pairs, two opposite links being connected together by a 70 cross-bar, f². The links f f' are free to turn on their pivots, whereby the position of the rider-bar can be adjusted toward or from the base-plate by changing the inclination of the links, and the latter being all of the same 75 length the rider-bar always remains parallel with the base-plate.

G represents a cylindrical screw-nut, which is seated in a cylindrical bearing, g, formed in the lower front end of the rider-bar D, and H 80 represents a screw-bolt which engages with the screw-nut G.

i represents an inclined ear formed on the front end of the base-plate E, and i' is an elongated opening formed in the ear i. The bolt 85 H is inserted through the opening i', with its slotted head h bearing against the under side of the ear i. j represents a recess formed in the end portion, d³, of the rider-bar below the cylindrical nut G, to permit the bolt H to be 90 inserted through the threaded opening in the nut G, and j' represents an inclined socket or recess formed in the end portion, d³, above the nut G, to receive the free end of the bolt.

By inserting the end of a screw-driver in the 95 slotted head of the bolt H and turning the bolt, the nut G, engaging with the threaded portion of the bolt, is caused to ride up and down on the bolt. The nut G being fastened to the rider-bar in the cylindrical bearing g 100 causes the rider-bar D to be adjusted as the nut G is raised and lowered. The cylindrical

form of the nut G and its bearing permits the nut to oscillate or turn in the bearing *g* as the rider-bar is adjusted, and the sides of the recesses *j j'* above and below the nut are inclined 5 on opposite sides of the bolt to permit the free movement of the bolt.

n represents a laterally-projecting stop formed on opposite sides of the rider-bar *D*, and adapted to engage against the links *f* and 10 limit the upward movement of the rider-bar.

The portion of the door *A* to which the hanger is attached can be readily raised or lowered, as may be necessary to level or adjust the door, by turning the bolt *H*, and the 15 rider-bar is adjusted so as to be parallel with the upper edge of the door at all times.

My improved hanger is simple in construction and possesses the requisite adjustability, which enables the door to be adjusted and leveled, and is strong and durable, and will support 20 very heavy doors.

I claim as my invention—

1. In a door-hanger, the combination, with the base-plate and rider-bar, of connecting-links pivoted to the base-plate and rider-bar, 25 and supporting the rider-bar on the base-plate, and an adjusting-screw and nut, which adjustably connect also the rider-bar with the base-plate, substantially as set forth.

2. In a door-hanger, the combination, with 30 the base-plate *E* and rider-bar *D*, of pivoted bars or links *f f'*, connecting the rider-bar with the base-plate, a cylindrical screw-nut, *G*, seated in the rider-bar to turn therein, and an adjusting-screw, *H*, substantially as set 35 forth.

Witness my hand this 16th day of September, 1884.

EDWARD C. STEARNS.
